(57) CLAIM

The ornamental design for a pet bathtub, as shown and described.

DESCRIPTION

FIG. 1 is a top perspective view of a pet bathtub, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 1;

FIG. 10 is an enlarged detail view of area 10 in FIG. 1; and,

FIG. 11 is an enlarged detail view of area 11 in FIG. 2.

The broken lines in the drawings illustrate the portions of the pet bathtub, which form no part of the claimed design.

The dash-dot-dash broken lines represent the boundaries and indicator of the enlarged view that form no part of the claimed design.
